UNITED STATES PATENT OFFICE.

OSWALD S. MEARS, OF BLOOMTOWN, VIRGINIA, ASSIGNOR OF ONE-HALF TO
H. C. DARBEE, OF SEAFORD, DELAWARE.

SHIP'S RUDDER.

SPECIFICATION forming part of Letters Patent No. 717,590, dated January 6, 1903.

Application filed April 24, 1902. Serial No. 104,513. (No model.)

To all whom it may concern:

Be it known that I, OSWALD S. MEARS, a citizen of the United States, residing at Bloomtown, in the county of Accomac and State of 5 Virginia, have invented a new and useful Ship-Rudder, of which the following is a specification.

This invention relates generally to ship-rudders, and more particularly to a supplemental or emergency rudder which is normally contained within the ship or vessel and is not brought into action or operation unless the main rudder is carried away or becomes unmanageable. As a general rule a ship is 10 only provided with one rudder, and when this rudder is carried away by the heavy sea and by striking an obstruction the ship is unmanageable until another rudder can be rigged and brought into operation. I am also 15 aware that a supplemental rudder has been arranged adjacent to a main rudder and held inoperative so long as the main rudder is in position. This supplemental rudder, however, is liable to be carried away the same as 20 the main one.

The object of my invention, therefore, is to provide a supplemental or emergency rudder which is normally contained within a vessel and is therefore not exposed the same as 25 the main rudder, said supplemental rudder being capable of being moved into or out of operation, as desired, and by mechanism contained within the vessel.

With these objects in view the invention 30 consists, essentially, in providing a longitudinal chamber adjacent to the stern-post of a vessel, said chamber having side openings adjacent to the said stern-post, and a rudder movable within the said chamber and adapted to be moved rearwardly into the open space, and means for supporting and moving the said rudder.

The invention consists also in certain details of construction and novelties of combination, all of which will be fully described 40 hereinafter and pointed out in the claims.

In the drawings forming a part of this specification, Figure 1 is a view showing the stern end of a vessel, the supplemental rudder being moved into operative position for the pur-

pose of more clearly illustrating its location and operation. Fig. 2 is a sectional view of the ship, the supplemental rudder being arranged within the vessel, said view also illustrating in elevation the mechanism for moving the said supplemental rudder in an operative position; and Fig. 3 is a sectional view taken on the line 3-3 of Fig. 2.

Referring to the drawings, A indicates the hull of the vessel, B the stern-post, B' the 60 keel, C the main rudder, and D the rudder-post, all of which are of the usual construction.

The ship is provided with a longitudinal chamber E in alignment with the stern-post 65 B and adjacent thereto, said chamber having side openings E' adjacent to the juncture of the stern-post and keel, as most clearly shown in Figs. 1 and 2. The supplemental or emergency rudder F is normally contained within 70 the chamber E and in advance of the side openings E', said rudder being pivotally connected to a movable stern-post G and provided with a rudder-post H. Movable stern-post G is supported at its upper end by means 75 of a suitable carriage G', which travels upon a track G², and at its lower end is arranged a bearing-roller G³, which travels upon the keel, thereby rendering the movement of the stern-post G easy and accurate. In order to 80 move the stern-post in or out for the purpose of projecting the supplemental rudder into or out of operation, I employ the rods I, which are connected to the said supplemental stern-post, said rods working through a beam K, 85 which forms the front wall of the chamber E, and these rods I also pass through a second beam K', which serves as a guide to hold the said rods in their proper parallel position. These rods I are connected by a cross-head 90 L, which works upon a screw M, journaled in suitable bearings mounted in the beams K and K', said screw having a gear N arranged upon its forward end, said gear having a pinion O meshing therewith, which pinion is operated by the shaft P, driven by any suitable power. It will thus be seen that by turning the screw M the cross-head L is caused to travel thereon, and consequently operate the 95 supplemental stern-post G, which carries the 100

supplemental or emergency rudder F. It will thus be understood that when the main rudder C is carried away the screw is turned to project the supplemental or emergency 5 rudder F rearwardly into the open space E', and the supplemental emergency rudder thus becomes effective or operative for the purpose of steering the vessel. Any suitable means may be employed for turning the screw 10 for the purpose of moving the rudder in or out.

Having thus fully described my invention, what I claim as new, and desire to secure by Letters Patent of the United States, is—

15 1. The combination with the ship having a chamber adjacent to its stern-post, said chamber having side openings adjacent to the said stern-post, of a movable rudder and post to which it is connected, and means for moving 20 said post and rudder for the purpose specified.

2. The combination with a ship having a chamber adjacent to its stern-post, of a supplemental rudder located in said chamber 25 and adapted to move rearwardly to bring the

same in operation, and means for moving the said rudder, as described.

3. The combination with a ship having a main stern-post, of a longitudinal chamber adjacent to the said stern-post, a supplemental stern-post, a supplemental rudder connected to said stern-post, the longitudinal movable rods connected to the said supplemental stern-post, and means for moving the said rods for the purpose specified. 30

4. The combination with a ship having a chamber adjacent to its stern-post, of a supplemental stern-post having rolling supports at its upper and lower ends, a supplemental rudder pivoted to the supplemental stern-post, the rods connected to said supplemental stern-post, the cross-head connecting the rods, and means for operating the cross-head, whereby the supplemental rudder is moved into or out of operation, substantially as described. 40
